[57] CLAIM

The ornamental design for a changeable cover for a golf bag, as shown and described.

DESCRIPTION

FIG. 1 is an isometric view taken from the top, front and right side of a changeable cover for a golf bag showing my new design;

FIG. 2 is a left side elevational view thereof;

FIG. 3 is a rear elevational view thereof; and

FIG. 4 is a bottom plan view thereof.

FIG. 1

FIG. 4

FIG. 3
